UNITED STATES PATENT OFFICE.

PETER A. WERNER, OF OAKLAND, CALIFORNIA.

DESIGN FOR A FACEPLATE FOR AUTOMOBILE SIGNAL LIGHT.

Application filed September 20, 1924. Serial No. 10,839. Term of patent 3½ years.

To all whom it may concern:

Be it known that I, PETER A. WERNER, a citizen of the United States, residing at Oakland, in the county of Alameda and State of California, have invented a new, original, and ornamental Design for Faceplate for Automobile Signal Light, of which the following is a specification, reference being had to the accompanying drawing, forming a part thereof:

The figure in the drawing is a front view of a face plate for automobile signal light showing my design.

I claim:

The ornamental design for a faceplate for automobile signal light as shown.

In testimony whereof I affix my signature.

PETER A. WERNER.
